LOUIS W. GREVE, OF CLEVELAND, OHIO, ASSIGNOR, BY MESNE ASSIGNMENTS, TO THE CLEVELAND ROCK DRILL COMPANY, OF CLEVELAND, OHIO, A CORPORATION OF OHIO.

FLUID-OPERATED TOOL.

1,135,178.

Specification of Letters Patent. Patented Apr. 13, 1915.

Application filed November 18, 1913. Serial No. 301,780.

To all whom it may concern:

Be it known that I, Louis W. Greve, a citizen of the United States, residing at Cleveland, in the county of Cuyahoga and 5 State of Ohio, have invented certain new and useful Improvements in Fluid-Operated Tools, of which the following is a specification.

The invention relates to fluid operated tools or machines, and particularly to fluid operated rock drills. The invention has for its primary object the provision of a simplified structure for securing the results as set forth in my application Serial No. 792,700, filed October 1, 1913. In the structure of 15 the said application the stoppage of the hammer piston, while still permitting a flow of air through the drill steel and to the drill rotating means, was secured by the admission of air (controlled by the throttle valve) to one end of the automatic main valve whereby such valve was moved to and held in one extreme of movement. My present invention contemplates securing the 25 same result by the use of a simplified arrangement. Briefly stated, this is accomplished by doing away with the passage from the throttle valve to one end of the automatic main valve and by rearranging 30 the exhaust ports so that the main valve and the piston are stopped by the closure of the exhaust passage, which closure is preferably accomplished by means of the manually controlled admission or throttle 35 valve. Thus the throttle valve when in one position permits the normal operation of the apparatus with the hammer piston and drill rotating means working in the usual way, and when the throttle valve is in another position the exhaust from the cylinder is cut off, thus stopping the movement of the hammer piston and main valve, while 40 permitting a continuous flow of air to the drill rotating means and to the front end 45 of the cylinder and through the hollow drill steel. One embodiment of the invention is illustrated in the accompanying drawing, wherein—

Figure 1 is a longitudinal section through 50 the machine with the operating parts thereof in one position, Fig. 2 is a similar longitudinal section through a portion of the machine, with the operating parts in another position, Fig. 3 is an enlarged section 55 through the machine at the throttle valve,

and Fig. 4 is a section through the machine at the throttle valve, showing such throttle in a position different from that of Figs. 1 and 2.

Referring first to the general arrangement of parts as shown in Figs. 1, 2, and 3, 60 1 is the main cylinder of the machine carrying the hammer piston 2 and the anvil 3; 4 is the cylinder of the main or controlling valve 5; 6 is the throttle valve for controlling the admission of fluid to the apparatus; 7 is the drill steel angular in cross section and slidably but non-rotatably fitting the chuck 8; 9 is a transversely working piston for securing the step-by-step rotation of the chuck and the drill steel carried thereby; and 10 is a valve for controlling the movements of the piston 9.

The chuck 8 is operated by means of a ratchet wheel 11 engaged by a segmental 75 member 12 toothed to fit the teeth of the ratchet wheel and having its upper end engaged by the piston 9, so that the oscillation of the piston rocks the member 12 back and forth and causes a step-by-step rotation of 80 the ratchet wheel 11 and the chuck 8 upon which it is mounted. This mechanism for securing the step-by-step rotation of the chuck and drill steel is shown, described and claimed in my co-pending application 85 Serial No. 784,359, filed August 12, 1913, and no detailed explanation or claim with respect to this structure is therefor made in the present application.

The hammer piston 2 is controlled from 90 the valve 5 which reciprocates and alternately admits pressure to the opposite ends of the piston hammer to secure its reciprocation. Substantially the same valve mechanism and arrangement of ports for securing the reciprocation of the hammer piston is disclosed in the patent to Richards No. 929,111 of July 27th, 1909, and no claim is made for this specific mechanism or arrangement of ports. In view of the fact 95 that this mechanism is a part of the prior art and fully disclosed in the patent to Richards, only sufficient explanation of such mechanism will be made in the present application as is necessary to an understanding of my invention and improvement to be later explained. The relation of the valve 5 and hammer piston will be most readily understood by a brief description of their operation. When the valve 5 and hammer piston 100

105

110

are in the position indicated in Fig. 1, fluid pressure from the throttle valve 6 is admitted through the passage 12^a, passes through the passage 13 in the plug 14, and thence through the inclined passage 15 to the groove 16 in the valve cylinder, thence to the groove 17, and finally to the front side of the hammer piston 2 via the passage 18. At this time pressure is being supplied to the chambers 19 and 20 at opposite ends of the valve 5, through the passages 21 and 22, the pressure in the chamber 19 being greater than that in the chamber 20 by reason of the fact that the passage 21 is larger than the end of the passage 22 leading into the chamber 20, there being a constant discharge from each of chambers through the small passages indicated at the upper sides of the chambers. The passage 21 has two openings 43 and 44 into the cylinder.

When the piston 2 moves to the rear as indicated in Fig. 2, it covers the end of the passage 21 and the groove 22. The covering of the end of the passage 21 cuts off the supply of pressure to the chamber 19 at the end of the valve 5, so that the pressure drops in this chamber, while the covering of the groove 22 causes an increase in the chamber 20, such increase being due to the fact that the groove is supplied with air from the inclined passage 15, by means of the passage 23. The valve is thus moved to the left to the position indicated in Fig. 2. This movement to the left of course cuts off the supply of air through the passage 18 and permits a supply of air from the inclined passage 15 to the left hand end of the hammer piston, via the groove 24 and passage 25, so that pressure is applied to move the piston to the right. The movement of the piston to the position indicated in Fig. 2 uncovers the end of the exhaust passage 26, such exhaust passage leading to the rear end of the machine and having its rear end open in the normal operation of the apparatus.

As the piston hammer 2 moves to the right from the position of Fig. 2 exhaust occurs from the front side of the piston via the passage 26 and via the passage 18, groove 17, groove 27, and passage 28, such passage 28 leading into the passage 26, so that all of the exhaust from the front side of the piston passes to the rear through the passage 26, with the exception of a certain amount which passes through the drill steel as hereinafter set forth. It will be seen that in the matter of the exhaust arrangement for the front end of the piston the structure differs from that of my application 792,700 wherein the exhaust flowing through the passage 18 to the groove 17 escapes through a hole in the valve casing, adjacent the groove 17, instead of passing down to the exhaust passage 26. The same distinction

exists with respect to the exhaust from the rear side of the piston hammer 2. When the piston hammer moves to the left from its position as indicated in Fig. 1, a part of the exhaust escapes into the passage 26 via the short passage 29, while another portion of the exhaust escapes into the same passage 26 via the passage 25, groove 24, groove 31, and passage 32. It will be seen that this latter exhaust arrangement differs from that of my application 792,700 in that in such application the exhaust from the groove 24 passes through the adjacent opening or passage in the top of the valve casing instead of passing down to the passage 26. The main distinction therefore over the apparatus of my prior application resides in the fact that all of the exhaust with the exception of what passes through the drill steel flows through the passage 26 to the rear of the machine and out past the throttle valve, whereas in the prior application only a part of the exhaust escapes through the passage 26, the remainder thereof escaping through the holes or perforations in the valve casing 4 above the main valve 5. As a result the exhaust can be entirely controlled from the throttle valve 6, which result could not be accomplished in the structure of my prior application.

The throttle valve 6 as illustrated in Fig. 3 consists of a hollow tapering plug held upon its seat by air pressure and provided with a handle 33. A ball 34 fits in recesses in the plate 35 carried by the handle, and serves to maintain the valve yieldingly in various positions to which it is turned, the ball 34 being spring held as illustrated, and constituting a construction well known in the art.

The throttle valve has three main positions, the first of which is illustrated in Fig. 4, the second in Fig. 1, and the third in Fig. 2. When the valve is in the position illustrated in Fig. 4 the apparatus is out of operation, since the passage 36 leading to the drill steel rotating piston 9 is blanked, and since the passage 37 through the plug is out of registration with the passage 12^a. So that no air is being admitted to operate the hammer piston 2.

The position of the throttle valve 6 as illustrated in Fig. 1 is the usual running position. When the valve is in this position the passage 37 registers with the passage 12^a, admitting fluid to operate the hammer piston, and the passage 38 through the wall of the valve indicated in dotted lines is in registration with the end of the passage 36, so that fluid is admitted to operate the drill rotating piston 9. At this time also the exhaust passage 26 is in registration with the groove 39 extending longitudinally of the wall of the valve 6 as indicated in dotted lines in Figs. 1 and 3. One end of this

groove 39 registers with the end of the passage 26, while the other end of the groove registers with a passage 40 (see Fig. 3) leading through the wall of the cylinder, so that 5 when the groove 39 registers with the ends of the passages 26 and 40 there is a free escape of air from the exhaust passage 26 to the outer air.

The third position of the valve 6 is as indicated in Fig. 2. In this position the openings or passages 37 and 38 respectively, leading through the wall of the valve, register with the ends of the passages 12^a and 36, so that the operation to be expected is the same 15 as when the valve is in the position of Fig. 1. The result is the same in so far as the operation of the hammer piston 2 is concerned, for the reason that when the valve 6 occupies the position indicated in Fig. 2 the 20 groove 30 is out of registration with the end of the exhaust passage 26, and such exhaust passage 26 is blanked, thus trapping the air in the cylinder and preventing the 25 actuation of the hammer piston. At this time the valve 5 will be held in the right hand position indicated in Fig. 1, at such time admitting fluid pressure continuously to the front side of the hammer piston with an exhaust therefrom through the usual 30 passages 41 and 42 in the anvil and drill steel. Even when the hammer piston assumes the 35 position indicated in Fig. 2, the valve 5 is not moved from its right hand position, since the port 44 is uncovered, admitting a sufficient supply of air to the chamber 19 to 40 counteract the pressure received in the chamber 20 from the groove 22. It will be seen that the pressure to the right of the hammer piston under these conditions with 45 the exhaust closed is higher than is the case in the normal operation of the machine with the exhaust open, so that the pressure supplied from the port 44 to the chamber 19 is greater than in the normal operation of the machine. In the normal operation of the 50 machine with the exhaust open and with the hammer piston in the position of Fig. 2, the pressure supplied to the chamber 19 at the left of the valve 5 by reason of the port 44 is inconsequential, so that the pressure from the groove 22 is sufficient to hold the valve 5 in its left hand position as heretofore indicated.

It will be seen from the foregoing that by 55 moving the throttle valve to the position indicated in Fig. 2 the movement of the hammer piston is stopped while still permitting a discharge of air to the front side of the piston hammer and through the drill steel, 60 while still permitting a discharge of air through the passage 36 to the drill rotating means. It will also be seen that the stoppage of the piston hammer under the conditions above specified is secured entirely by 65 throttling the exhaust, thus distinguishing

from the operation in my application 792,700 referred to wherein an additional passage 31 was employed, leading to the chamber 19 and controlled by the throttle valve in order to secure the maintenance of 70 the valve 5 in its right hand position when it was desired to stop the piston hammer. In my present construction I avoid the necessity of this additional passage, by arranging the exhaust passages and ports in 75 such a manner that all of the exhaust with the exception of what passes through the drill steel is directed through the passage 26 controlled by the throttle valve, instead of allowing a portion of this exhaust to escape 80 through the top wall of the valve chamber as is done in the construction of my prior application. While the result achieved is the same in so far as the stoppage of the 85 hammer piston is concerned, the present arrangement is simpler, and the number of ports and passages in the throttle valve and the walls of the cylinder is reduced. Other advantages incident to the modification will be apparent to those skilled in the art. 90

It will be understood that the principle of invention involved is of broad application and not limited to the particular type of apparatus shown, but contemplates any and all apparatus wherein the stoppage of the 95 piston is secured by means of throttling the exhaust. For convenience, the throttling or blanking of the exhaust is preferably accomplished by means of the throttle valve, but it will be understood that this is not 100 necessarily the case, although the arrangement illustrated is the preferred one.

What I claim is:

1. In combination in a fluid actuated machine provided with a cylinder, a hammer piston in the cylinder, means for securing the automatic reciprocation of the piston with the alternate application of fluid pressure to the opposite ends of the hammer piston, exhaust passage means through 105 which substantially all of the exhaust from the rear side of the piston hammer passes, an exhaust passage directed to the front of the machine and leading from the front side of the piston hammer, and a throttle 110 valve which in one position blanks the said exhaust passage means leading from the rear side of the piston hammer and thus stops the movement of the piston hammer and at the same time admits fluid pressure 115 to the front side of the piston hammer.

2. In combination in a fluid operated drilling machine provided with a cylinder and a drill steel with a passage there-through, a hammer piston in the cylinder, 120 means for securing the automatic alternate application of fluid pressure to the opposite ends of the hammer piston, exhaust passage means through which substantially 125 all of the exhaust from one side of the 130

hammer piston passes, a communication from the other side of the hammer piston to the passage through the drill steel, and a throttle valve which in one position blanks 5 the said exhaust passage means and at the same time admits fluid pressure continuously to the other side of the hammer piston and through the drill steel.

3. In combination in a fluid operated 10 drilling machine provided with a cylinder, a drill steel and fluid operated means for rotating the drill steel, a hammer piston in the cylinder, means for securing the automatic alternate application of fluid pressure 15 to the opposite ends of the hammer piston, exhaust passage means through which substantially all of the exhaust from one side of the hammer piston passes, a supply passage leading to the said fluid operated 20 means for rotating the drill steel, and means whereby the said exhaust passage means may be blanked, thus stopping the hammer piston, while still permitting a flow of fluid pressure through said supply passage to the 25 drill rotating means.

4. In combination in a fluid operated 30 drilling machine provided with a cylinder, a drill steel and fluid operated means for rotating the drill steel, a hammer piston in the cylinder, means for securing the automatic alternate application of fluid pressure 35 to the opposite ends of the hammer piston, exhaust passage means through which substantially all of the exhaust from one side of the hammer piston passes, a supply passage leading to the said fluid operated means for 40 rotating the drill steel, and a throttle valve arranged so that in one of its positions the said exhaust passage means are blocked, stopping the hammer piston, while fluid pressure is supplied through the said supply passage to the drill rotating means.

5. In combination in a fluid operated 45 drilling machine provided with a cylinder, a drill steel with a passage therethrough, a hammer piston, and a main valve controlling the alternate application of fluid pressure to the opposite sides of the hammer piston and the exhaust from such sides, 50 exhaust passage means receiving exhaust escaping past the said main valve from one side of the said piston, and a throttle valve adapted to blank the said exhaust passage means thus stopping the hammer piston 55 while permitting a flow of fluid pres-

sure to the other side of the hammer piston and thence through the drill steel.

6. In combination in a fluid operated 60 drilling machine provided with a cylinder, a drill steel with a passage therethrough, a hammer piston, and a main valve controlling the alternate application of fluid pressure to the opposite sides of the hammer piston and the exhaust from such sides, exhaust passage means receiving exhaust escaping past the said main valve from both sides of the hammer piston, the fluid pressure at the front side of the hammer piston also exhausting partially through the drill steel, and a throttle valve adapted to blank the 70 said exhaust passage means thus stopping the hammer piston while permitting a flow of fluid pressure to the other side of the hammer piston and thence through the drill steel. 75

7. In combination in a fluid operated 80 drilling machine provided with a cylinder, a hammer piston, a drill steel, fluid operated means for rotating the drill steel and a main valve for controlling the alternate application of fluid pressure to the opposite sides of the hammer piston and the exhaust from such sides, exhaust passage means receiving the exhaust, escaping past the said main valve from one side of the said piston, and 85 means for blanking the said exhaust passage means and thus stopping the hammer piston while fluid pressure is being supplied to the said drill rotating means.

8. In combination in a fluid operated 90 drilling machine provided with a cylinder, a hammer piston, a drill steel, fluid operated means for rotating the drill steel and a main valve for controlling the alternate application of fluid pressure to the opposite sides 95 of the hammer piston and the exhaust from such sides, exhaust passage means receiving the exhaust escaping past the said main valve from both sides of the said piston, and means for blanking the said exhaust 100 passage means and thus stopping the hammer piston while fluid pressure is being supplied to the said drill rotating means.

In testimony whereof I have hereunto signed my name in the presence of the two 105 subscribed witnesses.
